GARMENT

Esther Cadous, New York, N. Y.

Application June 16, 1945, Serial No. 599,789

3 Claims. (Cl. 2—237)

1

My invention relates to the upper or waist portion of garments to be worn particularly by women and may be adapted for skirts, slacks and other types of women's garments.

Broadly, it is an object of my invention to provide a garment which is automatically adjustable to girths of varying widths without the necessity of additional cutting, sewing, or other tailoring, or the use of fastening means, such as hooks and eyes, zippers, buttons and button holes, generally used for retaining the garment upon the person; my garment retaining at all times the appearance of a finely tailored garment, which maintains its shape during the various movements of the body.

Another object of my invention is to provide in a garment a combination of elastic and inelastic areas so joined together to give the appearance of a graceful and hand tailored garment without the necessity of using pleats, tucks, or gathers.

Still a further object of my invention is to provide a garment with automatic waist and thigh adjustability without the use of pleats, tucks and gathers or the necessity of surplus material, or the use of various types of fastening means, which have heretofore been found necessary in this art.

Another object of my invention is to provide an automatically adjustable waist portion of a garment which assumes a graceful appearance and which presents a smooth and unpleated surface at the mid-section of the body.

A further object of my invention is to provide a garment which has a great many advantages of a foundation girdle without requiring the use of a girdle when my garment is worn.

Still a further object of my invention is to provide in such a garment, in addition to all the advantages heretofore described, a novel elastic section to hold the rest of the garment in wearable position without the need of an additional belt.

Another object of my invention is to provide in such a garment some means of abdominal support and for aiding and supporting the hip portions of the body.

Heretofore it has been a disadvantage in garments purchased, to recut and reset such garments in order to fit the different girths of each purchaser in order to assure a tailored appearance of the garment. It is also necessary to pleat, tuck, and gather the material in the abdominal region to provide a measure of adjustability for the varying girths of the purchasers; such garments do not generally find favor with the wearer since women usually prefer a smooth fitting, flat lying garment about the abdominal and waist region of the body.

2

The use of a band of elastic fabric forming the top portion of such a garment for adjustability does not solve the problem, since a rectangular elastic band requires the cloth of the garment along the line of jointure of both these areas to be pleated, tucked, or gathered to permit the inelastic area of the garment to expand to the increased girth. Such a result is unsightly and lacks gracefulness and the appearance of a tailored garment. If the cloth were not pleated, tucked or gathered, the strain of the increased girth would stretch the elastic portion but would unduly strain or possibly tear the inelastic portion.

15 In my garment all such disadvantages would be obviated, and an adjustable garment provided having all of the objects heretofore described which may be made by cutting the elastic portion so as to provide a line of jointure between the elastic and inelastic portion. This type of construction eliminates the need for unsightly pleats, tucks or gathers and various types of fastening means, and produces a garment which moulds itself to the shape of the body and fits 20 snugly and gracefully upon the person of the wearer. A garment so constructed for one girth and width about the waist and hips is readily and automatically adjustable to a person of large proportions. The garment, when used by a person of increased girth and width about the hips and waist, requires no cutting, sewing or other tailoring. When the garment is drawn over the legs and when the thighs are reached, which are generally the widest portions of the body, there is 25 no danger of abnormal strain or possible tearing of the inelastic fabric. My garment will easily pass such wider width without the necessity of using pleats, tucks or gathers or separable fastening means to compensate for such increased 30 width. The necessary elasticity is provided by the elastic members at the waist and hip portions. The fabric along the line of jointure remains smooth and gives a tailored appearance, the increase in width being automatically provided by 35 the elastic members at the waist and hip portions thus obviating the need of tucks, pleats, gathers and various types of separable fastening means. If the line of jointure of the elastic and inelastic fabrics had been cut horizontally across the garment, the inelastic cloth would have been placed 40 under an excessive strain in passing the thighs and might result in tearing or weakening the garment when drawn over the thighs.

45 My garment eliminates all of such disadvantages, obviating the necessity of a foundation

girdle and gives a neat, smooth and graceful appearance which is sought to be attained by the use of a foundation girdle. Furthermore, abdominal support is provided and also support for the hip portions of the body. My construction also permits the incorporation in the garment with an area which may be braced by bone or spring steels to provide additional support for the abdomen and other portions of the body, leaving the garment adjustable, neat, comfortable, tailored and graceful in appearance.

My invention also resides in the combination, and arrangement of parts and the details of construction as herein set forth and claimed.

In order to clearly explain and describe my invention to others, I have shown it applied to slacks and skirts although it may easily be applied to other articles of wearing apparel, such as trousers of all kinds, pajamas, tennis shorts, men's shorts and other articles to produce all of the objects and advantages above enumerated.

My invention is illustrated in the accompanying drawings, in which:

Fig. 1 is a front elevation of a skirt with the lower portion cut away.

Fig. 2 is a side elevation of the skirt shown in Fig. 1.

Fig. 3 is a front elevation of a modified skirt.

Fig. 4 is a front elevation of another modified skirt.

Fig. 5 is a front elevation of still another modified skirt.

Fig. 6 is a front elevation of still another modified skirt.

Fig. 7 shows an elevational sectional view taken along line 7—7 of Fig. 8 viewed in the direction of the arrow.

Fig. 8 is a front elevation in perspective of the upper portion of a pair of slacks showing the provision of a section opposite the abdomen and rear region, said section containing bone or spring steel members.

Fig. 9 is an elevational diagrammatic view of the section containing the bone or spring steel members.

Fig. 10 is a front elevation of a pair of slacks showing a further modification in the line of jointure in which the elastic area is interrupted by the inelastic fabric which is carried to the top of the slacks.

Fig. 11 is a front elevation of a pair of slacks showing another modification in the line of jointure.

Fig. 12 is a front elevation of a pair of slacks showing a further modification in the line of jointure.

Fig. 13 is a front elevation of a pair of slacks showing another modification in the line of jointure.

Similar numbers refer to similar parts throughout the several views.

Referring to the drawings, skirt 25 is made of ordinary fabric 26 of inelastic material, save for the limited stretch provided by placing the material on the bias, which fabric comprises the main portion of the garment, the balance of the garment being made of elastic fabric 27. The elastic fabric is preferably made of the type of cloth in which the threads are a combination of fabric and rubber yarns in order to provide elasticity in the resulting fabric. The elasticity in this fabric is in the direction of the width of the garment, that is, in a horizontal plane, and being substantially inelastic along its vertical axis.

This fabric is well known in the art and particularly in the girdle art.

In Fig. 1 the skirt is provided with front and back elastic sections 28 and 29, respectively, and substantially triangular sections 30—30 on each side of the garment. The arrows on sections 28 to 30, inclusive, represent the horizontal stretch of such elastic members and such sections are stitched together and also to the fabric 26 as shown in the drawing to produce a garment which fits gracefully and smoothly at the waist and hips and the upper portions of the thighs. The side portions 30 drop to a point 31 at the thighs in order to assure proper adjustability in the garment to persons of wider girth and proportions, thus permitting the garment to be drawn on without tearing the intermediate elastic cloth 26 and preserving the smoothness, grace and neatness of the garment. The horizontal stretch of the elastic members also permits uniformity of height of the bottom of the skirt from the ground. No pleats, gathers, tucks, buttons, button holes, hooks and eyes, zippers, or similar devices are necessary. The front and back elastic sections give the appearance of a belt or may be concealed by a belt, while still providing the added stretch for the garment. The comparative narrowness of the elastic front and back sections 28 and 29, while insuring proper fit, will not cause excessive perspiration at the waistline of the wearer. If such elastic members were to be made too wide in the height, in warm weather the wearer would be caused to perspire more freely.

In Fig. 3 the inelastic fabric 26 is carried between elastic front and back sections 32—32 respectively. The triangular side sections 30 are the same and the result of the action of this garment is very much like that shown in Figs. 1 and 2. All of the elastic members stretch horizontally.

In Fig. 4 all of the members are identical with that of Fig. 3 except that instead of straight sided triangular side sections, such side sections are curved as shown by line 34—34.

The figure shown in Fig. 5 is identical with that shown in Fig. 1, except that the triangular side sections are curved as shown at 35—35 instead of straight as shown in Figs. 1 and 2.

In Fig. 6 all the sections are identical with that shown in Fig. 5, except that the front and back elastic sections drop lower in the central portions as shown by numerals 36—36.

Referring to Figs. 7 and 8, there is disclosed a modification of my invention in which the garment is provided with sections 37 front and back, in constructing said sections, inelastic fabric is cut to a size and shape corresponding to lines c, d, e, f, and g as shown in Figs. 8 and 9. On to one face of the section there are affixed stays 38 either of bone or spring steel. These are confined upon the surface of the section by sewing strips of tape 39 over them. The sections thus completed are then made part of the garment by sewing the same within the garment, front and back as indicated, by sewing along lines c, d, e, f, and g as shown in Fig. 8.

In inserting sections 37 within the garment in the modification in my invention shown in Figs. 7, 8 and 9, outer seams are left unsewed for a short distance commencing below points 40 and 41 and along lines 42, 42. In this condition of the garment sections 37, the front and back are readily fitted within the garment, against the corresponding elastic sections, and are then stitched along lines c, d, e, f, and g to permanently affix the same.

to the garment; the bottom line of said sections shown in dotted lines in Fig. 8 is left hanging free and unsewed. The garment is then completed by completing the sewing of the seams to the top of the garment. The result is a garment which has the additional features of added support and contraction for these portions of the body to assure in certain instances additional neatness and grace in the wearing of ladies' apparel.

If desired, the garment may be provided with an elastic section in the front alone, or with the elastic section in the back alone, leaving the front or back respectively of inelastic fabric, if it is desired to obtain the advantage of my invention on one side of the garment; I prefer to use an elastic section, however, in the back and front.

In Fig. 10 the inelastic cloth 42 is carried between the elastic side sections 43—43 to the top of the garment. Sections 43 are stretchable horizontally as indicated by the arrows to provide an identical result to that of the heretofore described skirt except that the application is to slacks.

In constructing the garment the elastic and inelastic sections are cut separately, according to pattern and the two joined along the line of jointure by sewing. Of course, it is possible to prepare the trouser or leg region and to knit integrally with this section, a section of elastic fabric so as to produce a garment having the prepared line of jointure. In the usual method of manufacture, however, the garment will be made in the manner indicated out of two separate sections; the elastic and inelastic sections then being joined as indicated.

The elastic section may be comprised of a single front and single back portion, the two being sewed together. It may also be made of one piece or the elastic portion may be comprised of four quarters to wit: a front and back for the left side, and a front and back for the right side, the four sections being sewed together to form one unit, this being the preferred manner of construction.

In Fig. 11 the upper portion of the slacks is somewhat like that shown in Fig. 10, except that the side sections 44—44 are joined together at the central portion so that the elastic members present a horizontal stretch all around the waistline as indicated by the arrows.

In Fig. 12 the slacks shown are very similar to those shown in Fig. 11, except that the side sections 45—45 have their lower portions straight as shown at 46—46 instead of curved, and stretch horizontally around the waistline as indicated by the arrows.

The slacks shown in Fig. 13 are very much like those shown in Fig. 12, except that the side sections 47—47 have the lower portion of the front and rear portions cut so as to present points 48—48 as shown in the figure. The elastic members 47—47 provide horizontal stretch around the waistline.

In all of the above modifications, I employ the principle of having the line of jointure so designed that the lower portion of the side or hip

sections are in a lower plane than the lowest point of the central section of the elastic members, thus presenting an inelastic fabric section between the elastic side sections.

5 I claim:

1. A garment having a lower part of inelastic fabric to conceal the lower limbs of the wearer, an upper elastic band about the waist and hip regions of elasticity across the width of said garment, said elastic band being lowest at the thigh regions and narrower across the midsection of the body of the wearer the narrowness of the elastic band, at the midsection of the abdomen of the wearer, approximating that of a conventional belt, and a flat seam uniting said band at its lowermost boundary with the lower part of said garment whereby the region of union remains sufficiently elastic across the width of the garment to varying girths, to conform the same to the shape of the wearer.

10 2. A garment having a lower part of inelastic fabric to conceal the lower limbs of the wearer, substantially triangular side sections of elastic fabrics having horizontal stretch at the upper side portions of said garment, elastic front and back sections at the upper portion of said garment, said front and back sections joined to the upper edges of said side sections, said sections presenting a horizontal stretch around said garment, at

15 the midsection of the abdomen of the wearer approximating that of a conventional belt, said sections being stitched at their lower portion to inelastic material comprising the rest of the garment, providing an area with inelastic material

20 35 between said elastic side sections, whereby the upper portion of said garment has sufficient elasticity across the width of the garment to fit varying girths and to conform itself to the shape of the wearer.

25 40 3. A garment having a lower part of inelastic fabric to conceal the lower limbs of the wearer, substantially triangular side sections of elastic fabric having horizontal stretch at the upper side portions of said garment, elastic front and back sections at the upper portion of said garment joined to said side sections at the midsection of the abdomen of the wearer approximating that of a conventional belt, inelastic material on the bias joined to the lower portions of said elastic

30 45 sections, said inelastic material running to the top central portion of said garment whereby sufficient horizontal stretch is provided across the width of the garment for varying girths and to conform the same to the shape of the wearer.

35 50 55 ESTHER CADOUS.
